UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVET-FEEDING MECHANISM.

Application filed October 22, 1925. Serial No. 64,070.

This invention relates generally to a device for delivering rivets one-at-a-time and in unbroken order to a rivet setting machine.

A general object of the invention is to provide an improved rivet feeding mechanism of the hollow pick-up wheel type in which the rivets are fed into the pick-up member which in turn delivers them one-at-a-time to the machine.

10 The invention includes a cup-shaped pick-up member provided along its marginal portion with a series of rivet receiving slots so formed and arranged as to receive individual rivets which are properly disposed for the 15 purpose in a mass of rivets resting on the slotted portion of the wheel as it rotates.

A particular feature of the invention resides in the construction of the hollow pick-up member, the inner surface of which is 20 provided with a series of steps whereby the mass of rivets within the pick-up member is broken up and delivery of the rivets is facilitated.

Other features of the invention will appear as the description proceeds.

In the drawings, in which a preferred embodiment of the invention has been selected for illustration:—

Fig. 1 is a cross section of the rivet feeding device; and

Fig. 2 is a face view of the pick-up member.

Referring to the drawings for a more detailed description of the invention, a rivet feeding device is shown which includes a supply hopper 10. A shaft 11 is journaled in a boss 12 formed on the hopper. The rivet sorting and arranging member, or pick-up member, 13 is cup-shaped and is clamped 35 against a collar 14 on the shaft by a resilient washer 15 and nut 16. The rim of the pick-up member is provided with a series of rivet-receiving slots 17 which receive the individual rivets and deliver them to the receiving channel 21.

The peripheral wall of the pick-up member is outwardly flared, but instead of having a gradual slope is provided with a series of flat surfaces, or steps, arranged parallel

to the axis of rotation of the pick-up member. The mass of rivets delivered from the supply hopper is tumbled about within the pick-up member by rotating the shaft 11, and as a result the rivets are caused to fall toward and into the slots 17. It has been found that if the outer wall of the pick-up member is formed with a gradual slope the rivets tend to mat into a somewhat solid mass the entire weight of which presses the mass toward the receiving slots. And as a result the sorting of the rivets into the slots is impeded.

This objectionable action is avoided in the present invention by forming the peripheral wall of the pick-up member with the flat steps 18, 19 and 20. Each of these steps carries the entire weight of a certain number of the rivets in the drum. Hence the rivets do not form into a single mass and the rivets on the lower step 20 can move freely to fall into the receiving slots.

What is claimed is:—

1. In a rivet feeding device, a hollow rotatable pick-up member the inner peripheral wall of which is formed with a series of steps of substantial width disposed substantially parallel to the axis of rotation.

2. In a rivet feeding device, a rotatable cup-shaped pick-up member having receiving slots formed in the margin thereof and having its inner peripheral wall formed with a series of steps of substantial width disposed substantially parallel to the axis of rotation.

3. In a rivet feeding device, a rotatable cup-shaped pick-up member having receiving slots formed in the margin thereof and having its inner peripheral wall formed with a series of short flat steps arranged parallel to the axis of rotation of the drum.

4. In a rivet feeding device, a rotatable hopper, the inner circumferential wall of said hopper being provided with a plurality of circumferential shoulders separating steps of substantial width disposed substantially in a horizontal position.

In testimony whereof I affix my signature.

EDWIN B. STIMPSON.
